Primary Examiner — Nathan M Johnston*(74) Attorney, Agent, or Firm* — Lewis Roca Rothgerber Christie LLP(57) **CLAIM**

The ornamental design for a dispensing cabinet, as shown and described.

DESCRIPTION

FIG. 1 is a front left perspective view of a dispensing cabinet showing our new design;

FIG. 2 is a front right perspective view thereof;

FIG. 3 is a front elevation view thereof;

FIG. 4 is a left side elevation view thereof, which is a mirror image as the right side elevation view thereof;

FIG. 5 is a rear elevation view thereof;

FIG. 6 is a top plan view thereof; and,

FIG. 7 is a bottom plan view thereof.

The broken lines shown represent unclaimed subject matter and form no part of the claimed design.
